US00D860952S

(12) **United States Design Patent** (10) **Patent No.:** **US D860,952 S**
(45) **Date of Patent:** ** *Sep. 24, 2019

(54) **ADAPTER**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/574,361**

(22) Filed: **Aug. 15, 2016**

Related U.S. Application Data

(63) Continuation of application No. 29/501,659, filed on Sep. 5, 2014, now Pat. No. Des. 763,794.

(57) **CLAIM**

The ornamental design for an adapter, as shown and described.

DESCRIPTION

FIG. 1 is a front perspective view of an adapter in a first state showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof in a second state;

FIG. 10 is a rear perspective view thereof;

(Continued)

FIG. 11 is a front view thereof;
 FIG. 12 is a rear view thereof;
 FIG. 13 is a left side view thereof;
 FIG. 14 is a right side view thereof;
 FIG. 15 is a top view thereof; and,
 FIG. 16 is a bottom view thereof.

The dot-dash broken lines in the figures and the areas within the dot-dash broken lines show portions of the adapter that form no part of the claimed design.

1 Claim, 8 Drawing Sheets
